UNITED STATES PATENT OFFICE.

CHARLES GEARINGER, OF BLOOMSBURG, PENNSYLVANIA, ASSIGNOR TO THE MAGEE CARPET COMPANY, OF BLOOMSBURG, PENNSYLVANIA, A CORPORATION OF PENNSYLVANIA.

SHARPENING DEVICE.

Application filed February 27, 1923. Serial No. 621,604.

To all whom it may concern:

Be it known that I, CHARLES GEARINGER, a citizen of the United States, residing in Bloomsburg, Pennsylvania, have invented a 5 Sharpening Device, of which the following is a specification.

In the manufacture of certain pile carpets it is customary to weave the fabric upon a series of parallel wires each having 10 at one end a projecting knife blade and thereafter successively withdrawing these wires longitudinally out of the fabric so that said blades thereon cut the loops of thread which have been laid over the wire, 15 thus forming a pile. Under ordinary conditions, each wire after being used in the weaving of about eleven inches of carpet, has its blade so dulled as to require sharpening and as a consequence looms using pile 20 wires of the above type require an attendant whose duty is to continually sharpen the edges of the pile wire knives as long as the machine operates.

One object of the present invention is to 25 provide an attachment for a carpet or similar loom for weaving pile fabric, which shall include means for automatically sharpening the pile wire knives during the operation of the machine; the invention especially 30 contemplating a simple and substantial device which may be easily applied and which shall require a minimum of attention under conditions of use.

A further object of my invention is to 35 provide a device for automatically grinding the cutting edges of the knives of pile wires while the latter are firmly held in the fabric which has been woven around them, the arrangement being such that each knife 40 blade will be ground to substantially the same extent with the result that the fabric produced has a pile of uniform length and appearance.

These objects and other advantageous 45 ends I attain as hereinafter set forth, reference being had to accompanying drawings, in which,

Fig. 1 is a side elevation, to some extent diagrammatic, illustrating one form of my 50 invention as applied to a loom;

Fig. 2 is a plan, on a larger scale than Fig. 1, further illustrating my invention;

Fig. 3 is a front elevation of the grinding stone and certain of the associated parts;

Fig. 4 is a side elevation of the parts 55 shown in Fig. 3;

Fig. 5 is a vertical section on the line 5—5 Fig. 3;

Fig. 6 is a fragmentary side elevation of the knife blade end of a pile wire showing 60 the grinding stone in position to cooperate therewith.

In Figs. 1 to 6 of the above drawings 1 represents the lay of a loom which is mounted to oscillate with or upon a shaft 2. The 65 warp $y-y$ after passing through the reed 3, is woven upon a series of pile wires 4 and from thence the finished fabric x passes around a guide roller 5 to a beam 6 on which it is wound. The pile wires, as shown in 70 Figs. 2 and 6, each have one end formed to constitute a thin cutting blade 7 supported in a vertical plane on a suitable supporting table 8. The free extremity of each blade is 75 preferably given a slight lateral curve as indicated at 9 and it will be understood that the sharpened or cutting edge of the blade lies uppermost, so that as the wires are drawn out of the fabric x by the action of the pile wire carriage and its associated 80 mechanism (not shown), certain of the warp threads are cut to form the pile of the fabric.

Figs. 7 and 8 respectively a side and a 85 front elevation, the first partly in section, illustrating a modification of my invention; and,

Figs. 9 and 10 are respectively a side and an edge elevation of one of the grinding 90 wheels used in that form of the invention shown in Figs. 7 and 8.

In accordance with my invention and for the purpose of sharpening the edges of the blades 7, I mount an arm 10 on a portion 11 of the loom frame 1 on that side thereof adjacent the knife blade ends of the pile wires. This arm extends upwardly and has rigidly fastened to it a laterally projecting rod or spindle 12 on which is rotatably mounted an elongated sleeve 13. This sleeve has fixed 95 to it a suitably grooved or flanged pulley 14 and also a projecting arm 15 held in place by a set screw 16.

Suitably mounted on the free or outer end 100 of the arm 15 is an elongated grinding stone 105 of suitable abrasive material tapering toward its end and V-shaped in cross section, said stone in the present instance being ad-

justably clamped in a recess in the end of the arm 15 by a retaining plate 17 held in place by screws 17^a. The sleeve 13 is held longitudinally in place upon the spindle 12 between a flange or collar 18 thereon and a cotter pin or equivalent device 19 and said spindle may be adjusted parallel with itself to project at various distances above the pile wires, by moving it up or down in a slot 20 formed in the arm 10, it being possible to clamp it any adjusted position by tightening a retaining nut 21.

The various parts are of such dimensions and are so adjusted that rotation of the sleeve 13 will swing the grinding stone 22 downwardly between and in engagement with two blades of a pair of adjacent pile wires which are more or less firmly held in the fabric α , the tapered sides of said stone 22 being so formed as to properly contact with and in its movement to sharpen the cutting edges of said blades, as shown in Fig. 6.

For periodically and automatically oscillating the sleeve 13 so as to actuate the grinding stone as above described I mount on the shaft 2 of the lay a projecting arm 23 and extend a flexible cable or belt 24 from this arm upwardly around the pulley 14 and then down to one end of a spring 25 whose opposite end is fixed to the floor or some other fixed structure, the arrangement being such as to at all times maintain said belt in a taut condition.

With the above described arrangement of parts it is obvious that each time the lay moves toward the right in beating up the weft, the grinding stone 22 is swung downwardly between the blades of a pair of adjacent pile wires so that its inclined side or sides comes into abrasive engagement with either or both of the cutting edges of said blades. Its action is such as to at all times maintain said cutting edges in a sharpened condition best fitted to perfectly cut the threads woven over their wires when the latter are forcibly withdrawn from the fabric. As the lay swings toward the left, the spring 25 acts to so turn the sleeve 13 as to raise the grinding stone to the elevated position shown in Fig. 1, and as the operation of the loom causes the pile wires 4 to be successively moved toward the right, each downward swing of the grinding stone causes it to enter between a new pair of wires and sharpen another wire blade.

As a result of the above described operation, the cutting edges of the series of pile wires are all acted on to substantially the same extent by the grinding stone so that they are worn away uniformly and in cutting the threads of the fabric make a pile whose threads are uniform in length and appearance. The device is of such a nature that it will operate for long periods of time without requiring little if any attention,

although it is obvious that if desired the position of the grinding stone may be adjusted in its holder so that it will at all times properly engage the edges of the pile wire blades.

Without departing from my invention, I may provide a device other than that shown in Figs. 1 to 6 inclusive, for automatically maintaining the cutting blades of the pile wires at all times in a sharpened condition. For example, in place of the reciprocating sharpening stone, I may utilize one or more rotary grinding wheels in the manner indicated in Figs. 7 to 10 inclusive. For this purpose, I mount a cam 26 and a pulley 27, on a rotary shaft 25 connecting said pulley through a belt 28 with a second pulley 29 fixed to a sleeve 30 rotatably carried on a fixed spindle 31 adjacent one end thereof. Said spindle is mounted in and projects horizontally at right angles to a lever 32 fulcrumed on a bolt 33 carried by a portion 34 of the frame of the loom. At its lower end said lever has mounted on it a suitable roller 35 positioned to cooperate with the cam 26 so that as the shaft 25 is turned by power applied through a gear wheel 37, the lever 32 is caused to oscillate on its pivot or fulcrum 33.

Said lever is so mounted that the spindle 31 and hence the sleeve 30 projects immediately over and at right angles to the blades 7 of the pile wires 4, and on the spindle I mount one or more grinding wheels 38 each of which has a hub 39 slidably fitting on said sleeve 30, which it will be noted, is square in cross section. On the outer or free end of the sleeve, distant from the pulley 29, is fixed an abutment in the shape of a nut 40 against which the grinding wheels are at all times yieldingly pressed by coiled spring 41 operative on the sleeve between them and the pulley 29.

The grinding wheels are preferably sharply beveled toward their edges and each of them has a portion cut away beyond a line parallel with the diameter, so that when said wheels are so positioned that the straight portion 42 of their edge is substantially horizontal, the pile wires may be moved bodily without interference from said wheels. Under conditions of operation, the shaft 25 is continuously or intermittently turned as may be desired, so that the sleeve 30 and wheels 38 are likewise turned. The parts are so adjusted, however, that while the pile wires are being moved bodily with the fabric as this is moved during the take up, the wheels occupy the relative positions indicated in Fig. 9 so that they do not interfere with such motion of the pile wires. When, however, the latter are immovably held by the fabric, the rotation of the spindle causes the wheels 38 to be turned with the result that portions of their beveled

edges engage the upwardly projecting cutting edges of the pile wire blades. At the same time the spindle 31 and with it the wheels 38 thereon are swung bodily by movement of the lever 32 on its fulcrum under the action of the cam 26, so that during rotation of the wheel or wheels, the latter are moved longitudinally of the pile wire blades. Thereafter and while the straight edged 10 parts of the wheels are immediately over the pile wires, the latter are moved bodily with the fabric for a distance equal to the width of one wire, after which the above described sharpening operation is repeated 15 so that all of the wires are successively engaged and kept sharpened by the grinding wheels.

I claim:

1. The combination with a loom having 20 a series of bladed pile wires, of a device automatically movable during the operation of the loom to enter between two blades and to simultaneously engage both of them to sharpen them.
2. The combination with a loom having a series of bladed pile wires, of a device having its major portion located above the blades, the said device being automatically movable downward during the operation of 25 the loom to enter between two blades and to

simultaneously engage both of them to sharpen them.

3. The combination in a loom having a lay and bladed pile wires of a rotatably mounted spindle; a pulley and an arm on 35 said spindle; a grinding stone carried by said arm; and a belt connected to the lay and operative upon said pulley to cause the engagement of the grinding stone with the blade of a pile wire at each beat of the lay. 40

4. The combination in a loom having a lay and bladed pile wires of a rotatably mounted spindle; an arm and a pulley on 45 said spindle; a grinding stone carried by said arm; a second arm movable with the lay; a belt having one end connected to said second arm and passing over the pulley; with a spring connected to the other end of said belt.

5. The combination in a loom having 50 bladed pile wires of an oscillatory arm having a horizontal axis above the plane of the wires; an elongated tapered grinding stone projecting downward from said arm; and means for actuating the arm to cause the grinding stone to periodically swing between and sharpen the cutting edges of adjacent 55 pile wires.

CHARLES GEARINGER.
